UNITED STATES PATENT OFFICE.

ALBERT BALL AND THOMAS OFFICER, OF CLAREMONT, NEW HAMPSHIRE, ASSIGNEES
TO SULLIVAN MACHINERY COMPANY, OF CLAREMONT, NEW HAMPSHIRE, A COR-
PORATION OF MAINE.

DIRECT-ACTING ENGINE.

1,075,750.

Specification of Letters Patent. Patented Oct. 14, 1913.

Application filed August 30, 1907. Serial No. 390,750.

To all whom it may concern:

Be it known that we, ALBERT BALL and THOMAS OFFICER, both citizens of the United States, and residents of Claremont, 5 in the county of Sullivan and State of New Hampshire, have invented an Improvement in Direct-Acting Engines, of which the following description, in connection with the accompanying drawings, is a specification, 10 like letters on the drawings representing like parts.

Our invention relates to direct acting engines, and more particularly, though not exclusively, to means for effecting an effi- 15 cient control of such engines.

We have herein illustrated our invention as applied to an undercutting coal machine, and will refer to the advantage of such particular application thereof, but it is to be 20 understood that our invention is not limited to the particular use herein illustrated, but that the same may be usefully applied to other machines and engines.

Our invention will be best understood by 25 reference to the following description when taken in connection with the accompanying illustration of one specific embodiment thereof, while its scope will be more particularly pointed out in the appended 30 claims.

In the drawings: Figure 1 is a central longitudinal sectional elevation, partly broken away, of an under-cutting coal machine embodying one form of our invention; 35 Fig. 2 is a rear elevation on an enlarged scale of the air chest cap plate of the engine shown in Fig. 1; Fig. 3 is a fragmentary sectional plan, also on an enlarged scale, taken on the line 3—3 in Fig. 2; Fig. 4 is 40 a rear elevation on the scale of Fig. 1, showing the back of the cylinder with the rear cylinder plate partly broken away; Fig. 5 is a detail showing the reversing plate; Fig. 6 is a detail showing the reversing valve; 45 and Fig. 7 is a diagrammatic view showing the ports and passages affecting the operation of the motive means for the main valve.

Referring to the drawings, we have there- 50 shown an embodiment of our invention in a coal cutting machine, the engine for which, except as specifically pointed out, is substantially the same as shown in the prior Patent, No. 661,686, granted to us Novem- 55 ber 18, 1900.

The main cylinder 1 of the engine contains a reciprocating piston 2, from which projects a piston-rod or stem 3, to the outer end of which is attached the pick or other tool (not shown) to be operated by the engine. A rifle bar 4, of any usual construction, engages a co-operating part of the piston and acts to turn the pinion 5 located at its outer end. Movement of the pinion 5 operates a reversing valve 6 by means of a 60 rack 7 on its upper edge, the pinion and valve being located in a chamber 8, formed by a cap 9, bolted to the rear plate 10 of the cylinder 1. The rotation or partial rotation of the rifle bar 4 is effected by means 65 of a nut in the piston, as is usual in engines of this character.

The live air for operating the piston is admitted to the air chest 11 through the admission opening 12, and from the air 75 chest 11 through a port or passage 13 to the front end of the cylinder, a spring-actuated valve 14 being so located in this passage as to be raised by the air admitted through the port or passage 13, but preventing the return of air through that passage and thus insuring the formation of a compressed air cushion for the piston at the front end of the cylinder.

Admission of live air from the air chest 80 11 to the rear end of the cylinder is obtained through the port 15 and the co-operating and connected run-around port 16. The exhaust takes place from the front end of the cylinder through the branched or di- 85 vided port 17, the exhaust port 18 and the main exhaust space 19, and from the rear end of the cylinder through the ports 20 and 21 and the main exhaust space 19.

The valve 22 for controlling the admission 90 and exhaust is connected to and operated by a differential piston device 23, the larger end 24 of which operates in a cylinder 25 formed at one end of the air chest 11, and smaller end 26 of which operates in a cylinder 27 formed in the other end of the air chest 11. The chamber 8 receives live air from the chest 11 through a passage 28, and air is supplied to the cylinder 25 from the chamber 8 through a passage 29 (shown in Figs. 2, 3 and 4). This passage extends upwardly through the plate 10 (Fig. 4) into the cap 42 at the rear of the cylinder, opening into the right-angled branch 29^x which leads to the rear of the cylinder 25, the open- 100 105 110

ing of the passage 29 into the passage 29^x, however, being regulated by a throttling device to be more fully described. The exhaust from the cylinder 25 is discharged through a passage 30, an exhaust throttle valve 41 being provided for the passage, which valve will also be more fully described. The exhaust passage 30 leads horizontally from the cylinder 25 to the hollow interior of the valve chamber where communication is effected through the body of the valve 41 with the lateral passage 30^x extending laterally and thence downwardly through the cylinder plate 10 and having its mouth registering with a groove 31 in the back of the valve plate 32 (Fig. 5). The groove 31 is provided with the port 33, which in one position of the reversing valve 6 is connected by the bridge and the groove 34 with the port 35 and the groove 36, the latter also upon the valve plate, and having connection with the exhaust passage 37 leading through the walls of the cylinder plate 10 to the atmosphere. The back of the plate 32 is also provided with a longitudinal admission groove 38 registering with the mouth of the admission passage 29 and also with the port 39. The transverse reciprocation of the reversing valve 6 through the movement of the rifle bar pinion acts alternately to uncover the port 39 and to admit air from the chamber 8 through the port 39 to the cylinder 24 and exhaust the same to the atmosphere from said cylinder by bridging the ports 33 and 35. This operation is substantially the same as the corresponding device shown in our said prior Patent No. 661,686, and the same means for setting the plate in order to regulate the normal stroke of the main piston may be employed, such means being indicated at 40 (Fig. 4).

In the illustrated embodiment of our invention we have provided governing means for regulating, at the will of the operator, the stroke of the piston. While such means may be embodied in other forms than those we have herein shown, we have here provided controlling levers whereby the piston stroke may be regulated by varying the action of the differential piston and the main controlling valve, such variation in the illustrated embodiment of our invention being by way of retarding the valve movement. In the drawings we have shown means both for retarding the forward movement of the valve and thereby retarding the backward stroke of the piston and tool, and for retarding the backward movement of the controlling valve, thereby to retard the forward movement of the piston. These controlling means are such that movement of the piston will not only be retarded, but if desired, the piston may be held fixed in either extreme position, at will.

For retarding the backward movement of

the controlling valve there is provided a throttling valve 41 adapted more or less to close the exhaust passage 30, thereby to trap pressure within the cylinder 25 and prevent the differential valve from moving back into the position shown in Fig. 1, or requiring it to move backward into such position at an impeded rate of speed.

The exhaust throttle 41 has a tapered seat in a vertical opening or recess in the cap 42, the latter bolted to the back of the casing for the air chest 11. The bottom of the recess is closed by a plug 48, but the recess opens directly into the cylinder 25 through the passage 30. The valve 41 is provided with a port 44, which is adapted to register with the upper lateral branch of the passage 30^x (shown in Figs. 1, 2 and 3), so that the available cross-section of the latter may be varied. The valve is provided with an exterior handle 45 adapted to be turned in the horizontal plane by the runner and frictionally engaging with the coiled spring 46 seated in the cap 42 to prevent accidental displacement of the handle and valve.

If the handle 45 is turned to reduce the area of the exhaust passage 30^x and thereby choke the exhaust, the backward movement of the piston 24, under the influence of the constant pressure in the chamber 11, will be retarded, or it may be that the piston and its valve will be entirely brought to rest. This will result in retarding or entirely stopping the forward movement of the main piston 2 according to the extent to which the exhaust is throttled and the return movement of the main valve retarded. Therefore, the quickness with which the forward piston stroke takes place, may be varied by the runner, as desired, or the working piston may be forced up against the cylinder head and there held fixed.

In order to throttle the admission to the differential valve cylinder 25 there is provided a valve handle 47 adapted to be moved in a vertical plane at the back of the cap 42, the end of said handle engaging a ratchet or notched formation 48 upon the face of the cap to prevent its displacement, a spring 49 at the opposite end of the handle forcing the same into engagement with the ratchet.

The valve handle is pivoted to the valve stem 50, the latter lying directly across the upright admission passage 29, and so shaped that by turning the handle the said passage may be left open or wholly or partly closed. By moving the valve handle 47 to shut off the passage 29^x more or less from the passage 29 and, therefore, from the air, the admission to the cylinder 25 may be retarded and the forward movement of the piston 24 and its valve more or less retarded. This, in turn, will act to retard the backward movement of the main piston 2.

It will be seen that the runner has at his

command the two throttle valve levers 45 and 47, conveniently located, through which any desired control may be exercised over the movements of the differential piston and 5 thereby over the movements of the tool.

While we have shown and described in detail one specific embodiment of our invention, it is to be understood that the same is not limited to the details of construction, 10 or the specific form or relative arrangement of parts, or to the application here made of the same, but that extensive deviations from the details shown may be made without departing from the spirit of the invention.

15 Claims.

1. In a direct-acting, fluid-pressure engine, the combination with a cylinder, a piston and main valve controlling the same, of a differential pressure-actuated device for 20 moving the main valve, a reversing valve actuated by the main piston for admitting pressure to or exhausting the same from the larger area of said pressure-actuated device, and a manually operable throttle valve 25 for the exhaust from said pressure-actuated device.

2. In a direct-acting, fluid-pressure engine, the combination with a cylinder, a piston and main valve controlling the same, of a differential, pressure-actuated device 30 for moving the main valve, a reversing valve actuated by the main piston for admitting pressure to or exhausting the same from the larger area of said pressure-actuated device, and manually operable means for throttling the pressure admitted to or the 35 exhaust from the larger area of said pressure-actuated device.

3. In a direct-acting, fluid-pressure engine, the combination with a cylinder, a 40 piston and main valve controlling the same,

a pressure-actuated, valve-moving means, a reversing valve for said pressure-actuated, valve-moving means, said reversing valve being operated by movement of the main 45 piston, and a pair of throttle valves controllable by the operator of the machine for retarding the movement of the main controlling valve in either direction.

4. In a direct acting, fluid-pressure engine the combination with a cylinder, a piston and a main valve controlling the same and pressure fluid means for operating the main valve, reversing means for said pressure actuated means operated by 50 piston movement, and manually operable means for throttling the pressure supply to or exhaust from said pressure actuated means.

5. In a direct acting, fluid-pressure engine the combination with a cylinder, a piston and a main valve controlling the same, a pressure-actuated, valve-moving means, a reversing valve for said pressure-actuated, valve-moving means, said valve being operated by movement of the main piston, a throttling valve for retarding the escape of the exhaust from the valve-moving means and thereby the movement of the main, controlling valve, a handle for said throttle valve, and means for holding said handle in any one of a series of finely graduated positions.

In testimony whereof, we have signed our names to this specification in the presence 70 of two subscribing witnesses.
